UNITED STATES PATENT OFFICE.

CHARLES R. MESTON AND HERBERT I. FINCH, OF ST. LOUIS, MISSOURI, ASSIGNEES TO THE EMERSON ELECTRIC MANUFACTURING COMPANY, OF ST. LOUIS, MISSOURI, A CORPORATION OF MISSOURI.

ADJUSTABLE OSCILLATING FAN.

1,259,545.

Specification of Letters Patent. Patented Mar. 19, 1918.

Application filed January 2, 1914. Serial No. 809,935.

To all whom it may concern:

Be it known that we, CHARLES R. MESTON and HERBERT I. FINCH, citizens of the United States, residing at city of St. Louis, 5 State of Missouri, have invented a certain new and useful Improvement in Adjustable Oscillating Fans, of which the following is a full, clear, and exact description, such as will enable others skilled in the art to which 10 it appertains to make and use the same, reference being had to the accompanying drawings, forming part of this specification, in which—

Figure 1 is a sectional elevation of our 15 improved fan oscillating mechanism taken on line 1—1 of Fig. 2.

Fig. 2 is a side sectional elevation of our improved fan oscillating mechanism taken on line 2—2 of Fig. 1.

Fig. 3 is a horizontal section of a portion 20 of our improved fan oscillating mechanism, the same being taken on line 3—3 of Fig. 2.

Fig. 4 is a diagram illustrating the various quadrants within which the fan may be 25 adjusted to oscillate by certain adjustments of the mechanism.

Fig. 5 is a diagram illustrating the various arcs indicative of the various degrees 30 of oscillation for which the fan may be set by certain adjustments of the oscillating mechanism.

Our invention relates to oscillating mechanisms designed particularly for electric fans, and has for one of its objects the provision of a mechanism whereby the direction 35 of the fan's oscillatory movement may be varied, and as another object, the provision of a mechanism whereby the degree of oscillation of the fan may be varied.

40 A further object of our invention is to provide a form of automatically operable adjusting mechanism which shall operate as a safety device by automatically limiting the degree of oscillation of the fan when its movement is impeded by an object interposed in its path.

50 A further object of our invention is to provide a very simple, strong and easily adjusted operating mechanism, comprised of very few parts and adapted to be economically manufactured.

Further objects of our invention will be hereinafter pointed out or will become ob-

vious upon an understanding of the construction and operation of the device. 55

By reference to the drawings, it will be understood that our invention contemplates a suitable base, standard or bracket 1, which acts as a support for the fan motor casing which is represented at 2. The motor casing 60 2 may be mounted upon the support 1 by means of an adjustable mounting 4 relative to which the motor casing is adapted to rotate by virtue of the rotary mounting 5.

Upon the motor casing 2 is carried a gear 65 casing 6 which forms a bearing for the projecting end 7 of the armature shaft carrying a worm 8. Journaled in the casing 6 is a worm wheel shaft 9 which carries a worm wheel 10 meshing with the worm 8, and a reducing pinion 11. The casing 6 has a depending sleeve 12 in which is journaled a stub shaft 14. Shaft 14 is supplied with a pinion 15 which meshes with pinion 11. Worm 8, wheel 10, and pinions 11 and 15 70 75 constitute transmission and reducing mechanism whereby motion is transmitted from armature shaft 7 to stub shaft 14 at a greatly reduced speed.

By reference to Fig. 2, it will be seen that 80 shaft 14 is supported to the rear of the pivotal axis of the fan, represented by the rotary mounting 5. To the lower end of shaft 14 is pinned a drum 16, which is made in two parts secured together by screws 17 (see 85 Fig. 3). The upper part of the drum has an upstanding annular flange 18 which forms a receptacle to catch superfluous lubricant. The upper and lower portions of the drum form bearings for an eccentrically disposed 90 pivot seat 19, and they are also provided with a seat for a detent consisting of the ball 20 and spring 21. The pivot seat 19 is adapted to be rotated in its bearings by means of a lever 22 which projects through 95 a slot 24 between the upper and lower sections of the drum 16. In the periphery of the pivot seat 19 are provided seats 25 with which the ball 20 co-operates under the influence of spring 21 to detain the pivot seat 19 in a selected position. By the exertion of sufficient pressure on lever 22 however, it is obvious that the seats 25 can be forced past the ball 20, so that the pivot seat 19 may be adjusted. 100

On a pin 26, which is located eccentrically

of pivot seat 19, is pivoted one end of a link 27. The location of pin 26 is such that when the pivot seat 19 is adjusted so that the seat 25^a at one end of the series is in engagement 5 with the detent ball 20, said pin 26 will be concentric of drum 16, and in axial alignment with shaft 14. The rotation of pivot seat 19 so as to engage the successive seats 25, throws pin 26 farther and farther off 10 center relative to the pivotal axis of drum 16 until, when the last seat 25 of the series is in engagement with the ball 20, the pin 26 is very close to the circumferential margin of drum 16. It is obvious that an increase 15 in the eccentric location of pin 26 relative to shaft 14 increases the throw of pin 26 and link 27 when drum 16 is rotated. The other end of link 27 is secured by a pivot pin 28 to the mounting 4 in a manner 20 hereafter to be described.

By virtue of the mechanism thus far described, it will be obvious that as shaft 14 is rotated by rotation of armature shaft 7, it will rotate drum 16 to which link 27 is 25 pivoted by pin 26 and pivot mounting 19. So long as pin 26 is concentric with shaft 14, it is obvious that the rotation of drum 16 will give no throw to said pin. Hence no movement will be given to link 27 and hence 30 the fan will remain stationary in its mounting 4. However when, by rotary adjustment of pivot seat 19, pin 26 is moved to a position eccentric of shaft 14, it is obvious that rotation of drum 16 will move said pin 35 about in a circle. This movement will deliver thrusts and pulls to link 27, and as link 27 is held against longitudinal movement by its connection with mounting 4, these thrusts and pulls operate to oscillate the fan on its 40 pivotal axis 5. Inasmuch as the throw of pin 26 is increased by an increase in its eccentricity relative to shaft 14, it is obvious that the degree of oscillation of the fan will be increased by increasing the eccentricity 45 of pin 26 relative to shaft 14 in the manner above described.

The coöperation of the detents with the seats 25 does not form a positive lock for pivot seat 19, but permits the rotation of 50 pivot seat 19 when sufficient pressure is applied. Consequently, if, during the oscillation of the fan an object is interposed in its path so as to intercept the movement of the fan guard or the motor casing, instead of 55 causing injury to the fan or the oscillating mechanism, the impedance to the fan's movement will simply cause the thrust on link 27 to reversely rotate pivot seat 19 and decrease the eccentric throw of pin 26. This will 60 decrease the extent of oscillation of the fan so that it will not strike the obstruction.

In the form shown, the pivot seat 19 is provided with six of the seats 25. One of these is for the stationary position of the 65 fan, and the other five represent five differ-

ent arcs of oscillation. The various arcs of oscillation are represented diagrammatically in Fig. 5. The maximum arc of oscillation is 90°, and the others are of various smaller extents. In the diagram, the radial lines 70 represent the center line of the fan.

It will be understood that the foregoing describes the operation of the mechanism which is designed for varying the arc or extent of oscillation of the fan. That now to 75 be described is for the purpose of selectively changing the direction, or varying the predetermined quadrant within which the fan may be adjusted to oscillate. These various quadrants are illustrated in the diagram, 80 Fig. 4. It will be understood that these quadrants represent the maximum oscillation of the fan in any one of the five predetermined different positions to which it may be adjusted, and it will be understood that 85 the degree of oscillation within any one of these quadrants may be limited by the mechanism and in the manner which has been described above.

The pivot 28, forming the attachment for 90 one end of link 27, is set in an adjustable collar 29 which is mounted upon the mounting 4 and capable of being rotated thereon. The collar 29 has a sleeve 30 which forms a seat for a locking pin 31, said locking pin 95 being impelled inwardly by a spring 35. The inner end of the locking pin 31 is adapted to coöperate with seats 34 formed in the mounting 4 and when said pin is engaged in one of said seats 34, the collar 29 is held 100 against rotation. The position of collar 29 may be changed by withdrawing locking pin 31 against the influence of spring 35 and then simply turning collar 29, using pin 31 or sleeve 30 as a lever. By virtue of the 105 connection afforded by link 27, whenever collar 29 is turned on mounting 4, the fan will be correspondingly turned on its pivotal mounting. Therefore, when collar 29 is turned to the left, the front of the fan will 110 be turned to the right, and vice versa. Inasmuch as the maximum arc of oscillation of the fan is 90°, it is obvious that by virtue of this adjustment, the fan may be positioned 115 on its mounting so that this 90° arc of oscillation will lie in any one of the several different directions. When locking pin 31 is engaged in the middle one of seats 34, the maximum arc of the fan's oscillation will be in the direction illustrated by the quadrant 120 C. When the collar 29 is adjusted so that the pivot pin is in the lowermost of the seats illustrated in Fig. 3, the quadrant of the fan's maximum oscillation will be that illustrated by quadrant A. Likewise, when the 125 collar is adjusted so that the pivot pin is engaged in the uppermost of seats 34 illustrated in Fig. 3, the quadrant of the fan's maximum oscillation will be that illustrated by the quadrant E, in Fig. 4. The interme- 130

130

diate seats will adjust the fan's direction of oscillation to the quadrants B and D respectively. In this diagram, the radial lines represent the fan's center-line.

5 These various features of adjustability have several advantages which will be readily recognized. In the first place, they do away with the necessity of moving the fan. In the second place, they enable the fan's 10 influence to be limited to a selected direction in case the fan is immovably attached, as to a wall bracket. In the third place, the feature of adjustability first described permits the fan's influence being limited to a selected 15 area which may be extended or restricted as desired.

In addition to these several features of utility, it is obvious that the invention provides a very simple, strong, economical and 20 easily operated mechanism, capable of a wide variety of adjustments, and affording a safety escapement which will prevent injury to the fan or to an object when such object is positioned in the path of the fan's movement.

Although we have shown and illustrated herein the preferred form of our invention, we are aware that such form is capable of 25 various changes and modifications, and we, therefore, do not desire that our invention be construed as limited to the single form shown.

What we claim is:

In an oscillating fan structure, the combination of a supporting member, a fan motor 35 revolvably supported thereon, a shaft adapted for operation by said motor and movable therewith relative to the supporting member, a drum member arranged for rotation by said shaft, a pivot seat revolvably mounted eccentrically on said drum member, a thrust member having one end pivotally connected eccentrically on said pivot seat and the other end pivotally connected to the supporting member, the said pivot seat being 40 provided with peripheral detent seats, and spring pressed detent means mounted in said drum member and adapted to coöperate with the peripheral seats of the pivot seat to retain the pivot seat in selected positions, said 45 pivot seat being provided with means whereby it may be manually manipulated against the influence of said detent means and said pivot seat being independently operable from said shaft for the purpose described. 50

In testimony whereof we hereunto affix our signatures in the presence of two witnesses, this 20th day of December, 1913.

CHARLES R. MESTON.
HERBERT I. FINCH.
